(57) **CLAIM**

We claim the ornamental design for a carabiner, as shown and described.

DESCRIPTION

FIG. 1 is a front perspective view of a carabiner.
FIG. 2 is a front elevation view of the carabiner shown in FIG. 1.
FIG. 3 is a right side elevation view of the carabiner shown in FIG. 1.
FIG. 4 is a left side elevation view of the carabiner shown in FIG. 1.
FIG. 5 is a rear elevation view of the carabiner shown in FIG. 1.
FIG. 6 is a top view of the carabiner shown in FIG. 1; and FIG. 7 is a bottom view of the carabiner shown in FIG. 1. The ornamental design which is claimed is shown in solid lines in the drawings. The broken lines in the drawings are for illustrative purposes only and from no part of the claimed design. A vial as disclosed in U.S. Patent No. D423,302 (Vial for Storing and Dispensing Films issued Apr. 25, 2000 and incorporated by reference herein) is shown provided in a receptacle of the carabiner.
